UNITED STATES PATENT OFFICE.

JAMES E. MITCHELL, OF LOWELL, MASSACHUSETTS, ASSIGNOR TO THE
MITCHELL TONGUELESS BUCKLE COMPANY, OF NEW YORK, N. Y.,

BUCKLE.

SPECIFICATION forming part of Letters Patent No. 732,368, dated June 30, 1903.

Application filed July 11, 1902. Serial No. 116,210. (No model.)

To all whom it may concern:

Be it known that I, JAMES E. MITCHELL, a citizen of the United States, and a resident of Lowell, in the county of Middlesex and State of Massachusetts, have made a certain new and useful Invention in Buckles; and I declare the following to be a full, clear, and exact description of the same, such as will enable others skilled in the art to which it appertains to make and use the invention, reference being had to the accompanying drawings, and to letters of reference marked thereon, which form a part of this specification.

Figure 1 is a perspective view of my buckle as applied. Fig. 2 is a perspective view of the buckle detached from the belt. Fig. 3 is a side elevation of the same. Fig. 4 is a section through the buckle on the line 4-4, Fig. 1. Fig. 5 is a longitudinal section through buckle and belt.

This invention has relation to buckles of the tongueless class primarily adapted for belts, and has for its object the provision of such a buckle of novel, simple, and efficient character.

With this object in view the invention consists in the novel construction and combination of parts, all as hereinafter described, and pointed out in the appended claims.

Referring to the accompanying drawings, the letter A designates the buckle-frame of skeleton form, crossed by the keeper-bar A'. The front bar B of this frame has a rabbeted rear edge or rabbet at b, forming a depressed or lower binding edge b'.

C is the securing or clamping bar for the strap or belt, pivoted at one end portion thereof to one of the lateral frame-bars C' in a groove c' thereof adjacent to the front frame-bar and having a spring-loop c³ at its opposite end portion arranged to detachably engage the other lateral frame-bar C' and lying within a similar groove c² thereof. This bar C has a path of movement in a plane at right angles and transverse to the plane of the buckle and is adapted to be swung within the recess b of bar B, lapping over binding edge b' above the same, but separated from the bottom of the recess by an interval to allow

passage of the belt therebetween, and is of 50 thin character, being usually stamped from sheet metal, its forward edge c, in connection with edge b', causing the belt to take a double or locking turn, as shown in Fig. 5 of the drawings, securely preventing slippage and 55 without injury to delicate fabrics.

Inasmuch as the bar C lies within the buckle-frame, it is protected by the frame from injury or displacement through hard knocks or rough usage. The spring-loop at the end 60 of the bar is readily disengaged from the buckle-frame, when the clamp-bar may be thrown backwardly entirely out of the way and leaving free the opening between the front frame-bar and the keeper-bar. In use 65 the end of the belt or strap lies close to the buckle, there being no protuberances or projecting parts to produce unsightly bulging.

My buckle may be cast, stamped from sheet metal, or made of wire. Its construction and 70 working are extremely simple, and its cost of manufacture trifling.

In use the clamping-bar presses the material of the belt or strap against the binding edge b', forming an S-form locking-bend of 75 the material at this point.

Having thus described my invention, what I claim as new, and desire to secure by Letters Patent, is—

1. In a buckle, the combination with the 80 front frame-bar having a thin depressed rear edge, of the adjacent clamping-bar hinged at one end, and having a detachable connection with the buckle-frame at the other end, said clamping-bar having a thin forward edge and 85 coöperating with said front bar to secure the belt in place, substantially as specified.

2. In a buckle, the combination with the 90 front frame-bar having a rabbeted rear edge, of the thin clamping-bar hinged at one end thereof, having a detachable spring engagement with the buckle-frame at the other end thereof, and adapted to lap the rabbet of said front bar, said bars coöperating to secure the belt in place, substantially as specified. 95

3. In a buckle, the combination with the front frame-bar thereof, having a rabbeted rear edge forming a depressed binding edge,

of the hinged clamp-plate having a path of movement in a plane at right angles and transverse to that of the buckle, and having a forward binding edge out of register with, 5 and coöperating with said binding edge of the front frame-bar to secure the belt or strap in position, substantially as specified.

In testimony whereof I affix my signature in presence of two witnesses.

JAMES E. MITCHELL.
